UNITED STATES PATENT OFFICE.

KENNETH E. STUART, OF LONDON, ENGLAND.

ELECTRIC-RAILWAY SYSTEM.

1,240,898.

Specification of Letters Patent. Patented Sept. 25, 1917.

Original application filed April 29, 1912, Serial No. 693,973. Divided and this application filed May 1, 1914. Serial No. 835,778.

To all whom it may concern:

Be it known that I, KENNETH E. STUART, a citizen of the United States, residing in the city of London, England, have invented 5 new and useful Improvements in Electric-Railway Systems, of which the following is a specification.

My invention relates to an electric railway system suitable for the despatch of mail, 10 parcels, etc., in which the moving cars or trains carry no motormen.

My invention resides in a system of control for the trains or cars involving a block system to prevent collision between cars or 15 trains, and resides more particularly in means for automatically accelerating, braking, starting and stopping the trains or cars.

My invention resides also in a system for indicating automatically in each station the 20 position of cars or trains on the line and for indicating whether a particular approaching car or train is to be stopped at the station in question or to pass it without stopping; and my invention resides in selecting means used in connection with such 25 a system.

My invention resides in other features hereinafter described and claimed.

For an illustration of one of the forms 30 of my invention reference is had to the accompanying drawings, in which:

Figure 1 is a diagram of the connections upon a car and between the car and the track and conductor rails and one type of 35 controller, which is shown in the "reversing position" or position in which it makes such connections as will cause the car to start backward.

Fig. 2 is a diagram of the same connections excepting that the controller is shown 40 in the "braking position" or position in which it makes such connections as will cause the car to be electro-dynamically braked.

Fig. 3 is a diagram of the same connections excepting that the controller is shown 45 in the "starting position" or position in which it makes such connections as will cause the car to start forward.

Fig. 4 is a diagram of the same connections excepting that the controller is shown 50 in the "through position" or position in which it makes such connections as will cause the car to continue at a predetermined 55 speed.

Fig. 5 is a diagram of the electrical apparatus and connections at a terminal station.

Fig. 6 is a similar diagram (shown for convenience in three parts) for the first 60 block section, supposed to adjoin the preceding section on the right.

Fig. 7 is a similar diagram for the second block section, supposed to adjoin the preceding section on the right. 65

Fig. 8 is a similar diagram for the third block section, which includes an intermediate station and is supposed to adjoin the preceding section on the right. This figure 70 also shows diagrammatically the electrical apparatus and connections at the said intermediate station.

Figs. 9 and 10 are similar diagrams for portions of the fourth and fifth block sections respectively, each supposed to adjoin 75 the preceding section on the right.

Fig. 11 is a diagram of the connections made by the contactors of the first block section when they are in the "braking position" or position which causes the train to come to 80 rest upon this section.

Fig. 12 is a diagram of the connections made by the same contactors when they are in the "starting position" or position to restart the train after it has been brought to 85 rest upon this section.

Fig. 13 is a diagram of the connections made by the same contactors when they are in the "through position," or normal position, which in this case are such as to retard the train to a speed at which it can 90 safely enter upon the curved portion of the line.

Fig. 14 is a diagram of the connections made by the contactors of the second block 95 section when they are in the braking position.

Fig. 15 is a diagram of the connections made by the same contactors when they are in the starting position. 100

Fig. 16 is a diagram of the connections made by the same contactors when they are in the through or normal position, which in this case are such as to accelerate the train again to full speed and then pass it over the remainder of the section at substantially 105 that speed.

Figs. 17, 18 and 19 are diagrams of the connections made by the contactors of the third block section when they are in the 110

braking, starting and through positions respectively.

Fig. 20 is a diagram of the connections made within the controller of the "braking section" of the terminal station when it is in the braking position.

Fig. 21 is a diagram of the connections made within the same controller when it is in the starting position.

10 Figs. 22, 23, 24 and 25 are diagrams of the connections made within the controller for the "approach section" of either station when it is in the reversing, braking, through and starting positions respectively.

15 Figs. 26, 27, 28 and 29 are diagrams of the connections made within the controller for the "unloading section," "loading section" or "siding section" of either station when it is in the reversing, braking, neutral and starting positions respectively.

20 Figs. 30 and 31 are diagrams of the connections made within the controller for the braking section of the intermediate station when it is in the braking and starting positions respectively.

25 Fig. 32 is a diagram of the connections made within the controller for the switch points of the intermediate station when it is in the "station position," or position in which the switch points are set to direct a car into the station.

30 Fig. 33 is a diagram of the connections made within the same controller when it is in the "past position" or position to direct a car past the station.

35 Fig. 34 is a side elevation, partly in section on the line 1-1 of Fig. 35, of one of the contactors above mentioned.

40 Fig. 35 is a plan view of the same, part being shown with the cover broken away.

Fig. 36 is an end elevation of the same, the left half being in section on the line 2-2 and the right half on the line 7-7 of Fig. 34.

45 Fig. 37 is a sectional end elevation of the same, on the line 8-8 of Fig. 34.

Fig. 38 is a horizontal section, some parts in plan, on the line 3-3 of Fig. 39, of a single ended relay.

50 Fig. 39 is a plan view of the same.

Fig. 40 is a section on the line 5-5 of Fig. 38.

Fig. 41 is an end elevation, partly in section, on the line 6-6 of Fig. 38.

55 Figs. 42 and 43 are side elevations, partly in section, and plan view, respectively, of a modified form of relay.

Fig. 44 is a diagram showing the curves of retardation from full speed to rest of an empty car and a loaded car when my system of equalizing the braking effect upon the two is employed.

Referring now to Figs. 1, 2, 3 and 4, T_1 and T_2 are contact conductor rails for the motor field and armature respectively, extending along the trackway and insulated

from the ground and from the track rails T_3 , T_4 . M is the electric motor driving the car through the gears G_1 and G_2 and wheels W_1 . S_1 and S_2 are collector shoes carried by the car and bearing upon the conductor rails T_1 and T_2 respectively. The electrical connections upon the car are from T_1 through the shunt field F_1 and the point 19 to the frame of the car F and thence through the wheels to and through the track rails T_3 . There is also a connection from T_2 through the differential series field F_2 and the brush B_4 , to the motor armature A_1 and thence through the brush B_3 , point 19, car frame F and wheels to the track T_4 .

70 There are thus three connections to the motor, *i. e.*, one to the shunt field, one to the armature, and a return connection common to both field and armature. These are used to start, stop and reverse the car in the following manner:

80 Upon certain sections of the line, which will be clearly indicated hereinafter, the conductor rails T_1 and T_2 , as well as both the track rails T_3 , are insulated from the similar 90 rails of the adjoining sections of the line and connected to a manually operated controller not upon the car. Upon such portions of the line the car may therefore be controlled by an operator at a distance. The 95 manner of doing this is illustrated in Figs. 1, 2, 3 and 4.

95 The controller used is merely an adaptation of a well-known commercial type having fingers bearing upon a common drum which in various positions makes various connections between them. In this case there are eight fingers and four positions of the drum. The fingers are numbered 11 to 18 inclusively and the connections established between them by the drum in each of its several positions are indicated by the lines joining them and passing to the right of them.

100 Referring to Fig. 3, it will be seen that there is a connection from the positive main 110 to the finger 12 and thence through the drum to the finger 11, which is connected to the conductor rail T_1 , which, it will be remembered, has a connection through the collector shoe S_1 to the shunt field of the motor M on the car. The finger 13 has a connection through the rheostat or resistance R_1 with the positive main and through the drum to the finger 15, which in turn is connected to the conductor rail T_2 , whence the connection 115 is through the collector shoe S_2 to the armature of the motor M through series field winding F_2 . The finger 16 is connected to the track rails T_3 and also through the drum to the finger 17, which is connected to the 120 negative main. As already explained, both the armature and shunt field have a return connection to the track rails T_4 . With the connections as shown in Fig. 3, therefore, the motor field F_1 will be excited to full 125 130

strength while the armature will receive current at a reduced voltage, which may be made suitable for starting the car from rest, and the series field F_2 is in opposition to shunt field F_1 , but the current flow through F_2 is not great, due to resistance R_1 , and therefore the motor field is not greatly weakened by F_2 . As the car is intended to move at slow speed only while under the control of these controllers, it is not necessary to provide another position in which the rheostat R_1 is cut out. Under certain circumstances to be explained later, however, it may be desired to keep the car moving uniformly at the reduced speed with which it arrives upon the portion of the line in question, and for this purpose another position of the controller is provided as shown in Fig. 4. In this position the connections are the same as before excepting that the finger 15 which supplies the motor armature is now connected through the drum to the finger 14 which receives current through a greater resistance than the finger 13.

The connections for braking the car are shown in Fig. 2. In this case the motor field F_1 is excited to full strength as before, while the armature instead of being connected to the positive main is connected through the drum and finger 16 to the track rails T_3 , thus completing a short circuit through the armature. Any rotation of the armature will now cause it to generate an electro-motive-force which on account of the low resistance of the armature circuit will cause a heavy current to flow which in turn resists the rotation of the armature, or in other words exerts a braking effect on the car. This armature current is in reverse direction, and, passing through series field F_2 , causes the latter to act cumulatively with the shunt field F_1 , to produce a still stronger field. As will be shown later, by interposing a suitable resistance in the armature circuit (not shown in Fig. 2) I regulate the braking effect so as not to damage the motor or cause the car wheels W_1 to skid on the rails T_3 .

The method of reversing the directions of the car is shown in Fig. 1. In this case it will be seen that the motor armature is connected through the drum to the finger 12, which receives the full voltage from the positive main. The return connection from the track rails T_3 is, however, no longer directly to the negative main but is through the drum and finger 18 to the negative main through the rheostat R_2 . The field connection from the conductor rail T_1 has also been transferred through the drum and finger 17 to the negative main direct. With these connections it will be seen that the shunt field is now connected in series with the armature, but in shunt or parallel with the rheostat R_2 . Thus, the current now flows

from the finger 15 through the conductor rail T_2 , the differential series field F_2 , and the armature to the point 19, where it divides, part returning through the fingers 16 and 18 and the rheostat R_2 to the negative main, while a part flows through the shunt field and fingers 11 and 17 to the negative main direct. As the resistance of R_2 is very great compared with that of the remainder of the armature circuit, the fall of potential through it at the instant of switching on the current with the motor at rest will be very nearly the full voltage of the power supply. In other words the shunt field will receive very nearly the full voltage of the mains across its terminals and will be excited to a corresponding degree. It will be noticed, moreover, that the direction of the current in the shunt field has been reversed, and is now the same as that of the series field, making a compound field. Without the latter, the motor would now develop a torque in the reverse direction approximating its normal starting torque. By means of the cumulative series starting turns the field is further strengthened and the torque developed in the reverse direction can be made to equal or exceed the normal direction starting torque.

It will be noted that the series turns are not essential to this method of reversing, but are useful. They are likewise useful in the operation of braking, since in this case the current in the armature is reversed and the series turns are cumulative with the shunt turns, as above described. It may also be mentioned that the differential series turns improve the constant speed characteristic of the motor in normal ahead running and if properly proportioned are therefore an advantage from every point of view. As the motor gathers speed when so reversed the current and consequently the fall of potential through the rheostat R_2 will diminish. This will weaken the shunt field exactly as the field of a series wound motor is weakened as it gathers speed. A shunt motor reversed in this way therefore develops series motor characteristics. But as I use this method of reversing only for side tracking and switching within the stations where the car is under control of the operator, this feature is not objectionable. This method of reversing avoids the use of an extra contact conductor rail, which would otherwise be necessary to provide a separate return connection from the shunt field for reversing the current through it.

The manual control of the car above described, *i. e.*, by means of controllers, is used only in or near the stations. At other points the movement of the car is independent of the operators, but subject to the automatic control of a block system.

Referring to Figs. 5, 6, 7, 8, 9 and 10, T_3

represents the track rails, T_1 the shunt field conductor rail and T_2 the armature conductor rail as before. $I_1, I_2, \dots$, are insulators serving to divide the track or contact conductor rails into the sections above referred to.

At the approach to each station it will obviously be necessary to provide means for bringing the car to rest. In Fig. 5 the 10 method of accomplishing this at a terminal is shown. This is accomplished by disconnecting the armature conductor rail T_2 from the source of current Se (connected to positive main pm and to negative main nm) and 15 connecting it to the track rail T_2 through a resistance while the field winding F_1 is separately excited at full strength, as already described. The minimum safe resistance in 20 the armature circuit is determined by the speed of the car, and as the car is retarded the resistance can therefore be cut out step by step. In Fig. 5, the sections of the armature conductor rail $I_1-I_2, I_3-I_4, I_4-I_5, I_5-I_6$ are each connected to the track rail 25 T_3 through successively smaller portions of the resistance or rheostat R_2 . The section I_2-I_3 is connected to the positive main pm , for reasons that will be explained later. The sections of the armature contact conductor 30 rail T_2 , such as $I_1-I_2, \dots$, which are for braking normally connected to the track rails T_3 I call "retarding sections." The section I_2-I_3 I call an "equalizer section." The whole series collectively I call a "braking 35 section."

The field conductor rail T_1 throughout the retarding sections, as well as elsewhere, is likewise divided into sections (as at $I_{51}, I_{52}, I_{53}, \dots$, Fig. 5.) which have to do with the 40 system of indicating in the stations the position of the cars in transit and also with the block system, both of which will be described later. Each section of the field conductor rail receives current through a series 45 solenoid in the relays $R_{21}, R_{22}, \dots$. These series solenoids are of negligible resistance so that the field conductor rail may, except in the case of sections that are under the control of controllers, be considered to be in 50 permanent connection with the positive main pm , causing the motor field F_1 to be excited as stated.

The operation of the retarding sections 55 will be better understood by reference to Fig. 44. In this figure, the full line 1^c is the curve of retardation of a loaded car from 30 miles per hour to rest, ordinates being proportional to speed and abscissæ to distances. In the case illustrated, on the first retarding 60 section, *i. e.*, I_1-I_2 , the speed is retarded from 30 to 15 miles per hour. Upon the equalizing section I_2-I_3 , the motor on the car receives current from the source of power tending to drive it, but the resistance 65 interposed between it and said source is so

calculated that the torque developed by the motor is insufficient to overcome the resistance of the car to forward motion, which therefore continues to be retarded, though at a reduced rate. The car is retarded on 70 the equalizing section from 15 to 10 miles per hour. On the remaining retarding sections, the speed is reduced from 10 to 5 miles per hour, from 5 to $2\frac{1}{2}$ miles per hour and from $2\frac{1}{2}$ miles per hour to rest respectively. 75

In Fig. 44 the dotted line $e\ c$ is the curve of retardation of an empty car arriving at the same speed as the loaded car.

The function of the equalizing section is as follows:

The braking effect of a short-circuited motor armature whose field is separately excited at constant strength is, with a given resistance in the armature circuit, proportional to the speed. In other words, for a 85 given speed it is the same for both the loaded and empty cars. But at a given speed the empty car possesses less energy than the loaded car, consequently it will be retarded more rapidly. In the case illustrated in Fig. 44 the empty car reaches the equalizing section with a speed of $13\frac{1}{2}$ miles per hour, as compared with 15 for the loaded car. At this reduced speed, however, the empty car receives a greater current from the source of power than did the loaded car, and gains in speed relatively to it. It leaves the equalizing section with a speed of 11 miles per hour as compared with 10 for the loaded car. From this point it 100 begins again to be retarded more rapidly than the loaded car and finally comes to rest at the same spot (20, Fig. 44).

With any system of braking depending upon friction there is not only a great variation in the distance required to bring a train to rest on account of variation in the coefficient of friction, but there is also a great difference between empty and loaded cars (100% or more). With dynamo-electric 110 braking this variation is reduced to about $12\frac{1}{2}\%$. By means of the equalizing section, however, it can be further reduced to a negligible quantity.

It will be observed that on each of the 115 retarding sections the speed is reduced in the same ratio (being halved in this case, except that on last section the speed is reduced to zero). The object of this is as follows:

The maximum allowable electro-dynamic braking effect, expressed as a torque in foot pounds, at the beginning of each section is limited either by the adhesion of the driving wheels or by the capacity of the motor, and is consequently the same for all of the sections. To procure suitable mean braking effect with a given number of sections, I prefer to make the mean braking effect upon each of the sections the same. This condi- 130

tion is secured by so proportioning the lengths of the sections and their associated armature circuit resistances that the braking effects at the initial ends of the sections are substantially equal, and the braking effects at the terminations of the sections are likewise substantially equal, it being remembered that the speed nevertheless is always decreasing; and furthermore, the ratio of the braking effect at the beginning of each section to the braking effect at the termination of each section is substantially the same for all sections with the exception of the last, in which case the same maximum braking effect is produced at the initial end of the last section, but the braking effect is reduced to zero as the car comes to rest. For instance, at the point at which it is desired that the motor braking should begin the resistance to be inserted in the armature circuit in order to give the maximum allowable braking torque is determined. With this factor known the rate of negative acceleration or braking is determined. From this the length of the section necessary to insure at its end a braking effect which bears the desired ratio to the braking effect at its initial end is determined. The next step is the determination of the resistance to be inserted in the armature circuit for the next succeeding braking section. This, however, is a function of the speed at the end of the preceding section and is therefore determined in the same way as the corresponding resistance for the first section. This process is followed out for the desired number of sections, and we have the following relation:

$$\frac{T_2}{T_1} = \frac{T_4}{T_3} = \frac{T_6}{T_5}, \text{ etc.},$$

in which T_1 is the braking effect or torque at the initial end of the first section, T_2 the effect at the end of the first section, T_3 the effect at the beginning of the second section, and T_4 the effect at the end of the second section, etc. It being remembered, however, that the braking effect is proportional to the speed and that the speed at the end of the first section is substantially equal to the speed at the beginning of the second section, and so on, we may write:

$$\frac{S_2}{S_1} = \frac{S_3}{S_2} = \frac{S_4}{S_3}, \text{ etc.},$$

in which S_1, S_2, S_3 and S_4 , are the speeds at the beginning of the successive retarding sections. If this law is followed it will be found that the successive retarding sections become shorter and shorter as in Fig. 44.

The retarding sections are normally at the entrance to the station, their function being to prevent the cars from entering the station except at the volition of the operator. When the cars have come to rest or been retarded to a safe speed, therefore, it is

necessary that the operator should be able to cause them to enter the station.

This is accomplished by connecting the retarding sections to a controller in the station by means of which the operator may by a movement of a lever disconnect them simultaneously from the track rail and connect them to the source of power.

In Fig. 5 this controller is shown at C_1 . It will be observed that the retarding section I_1-I_2 is permanently connected through the rheostat R_2 to the track rail and the equalizing section I_2-I_3 is permanently connected through the rheostat R_1 to the positive main pm . The operator thus has no control over the car until it has been retarded to a safe speed. The remaining retarding sections are, however, connected to the fingers 22, 23 and 24 of the controller C_1 , and in the position shown in Fig. 5, these fingers are connected through the drum to the fingers 25, 26 and 27. Thence 25 is connected directly to the track rail and 26 and 27 are connected to the track rail through the rheostat R_2 as previously stated. The connections made by the drum of this controller in this (the braking) position are shown again for clearness in Fig. 20, side by side with the connections made by it in the alternative or starting position (Fig. 21). From this figure it will be seen that in the starting position the fingers 22, 23 and 24 are connected to the finger 21, and from Fig. 5 it will be seen that the finger 21 is connected through the rheostat R_1 to the positive main. In this case there are no reversing or through positions of the controller. The functions of the finger 28 and the solenoid 29 will be explained later.

The braking section ends at I_6 , and at this point another section of the track, which I call the "approach section", begins. This section is under the control of the controller C_2 , which is similar to the controller that has already been described in connection with Figs. 1, 2, 3 and 4. It will be remembered that it has four positions, viz., reversing, braking, starting and through. For clearness, the drum connections in each of these positions are shown again in Figs. 22, 23, 24 and 25. The object of the through position may now be understood. It is that this approach section I_6-I_7 may serve as an equalizer section for trains that have been admitted from the braking section, the operation being the same as that of the equalizing section already described. By this means an empty car, arriving on this section at a speed less than desired speed because it has been to greater degree braked on the preceding braking section, will be accelerated because the current required for the acceleration is relatively smaller and occasions smaller drop of potential in the resistance R_1 , with the result that there is

impressed upon its motor armature a relatively higher voltage than in the case of a loaded car arriving under similar conditions.

The approach section in general enters the station and is used for shunting or switching the cars, hence the reversing, braking and starting positions.

From the approach section the car normally passes over a switch point or system of switch points which may direct it on to an unloading section or upon a siding, at the will of the operator. In Fig. 5, the unloading section is from I_7 to I_8 and a siding is shown from I_{10} to I_{11} . I_8 to I_9 is a loading section.

These three sections in the order last named are under the control of the controllers C_3 , C_4 and C_5 respectively. The controllers are all similar to each other, but differ from the controller C_2 in that they have no through position, the place of which is taken by a "neutral position," in which all connections to the section are interrupted. The drum connections for the several positions of these controllers are shown in Figs. 26, 27, 28 and 29. They are similar to those of C_2 except that instead of the two fingers 13 and 14 connected through different resistances to the positive main pm , there is but one, indicated at 33.

It will be noticed that the several controllers are not associated with the same rheostats R_1 , R_2 , R_3 and R_4 , either for receiving current through them from the source, or for braking purposes. The object in this is to avoid the use of the same rheostats for two sections upon which it may be desired to move trains at the same time, for if two trains were to take current simultaneously through the same rheostat the current and consequently the fall of potential through the rheostat would not be the same as when only one was taking current and neither train could develop the required starting torque.

It will be noted that the field conductor rail T_1 and the track rails T_3 of each of these sections under control of controllers having a reversing position are insulated from the adjoining sections as well as the armature conductor rail (as at I_{53} and I_{90} Fig. 5). This is necessary, as in reversing, the field conductor rail completely changes in its polarity, while a considerable difference of potential is created between the section of the track rail and adjoining sections owing to its being connected to the negative main nm through a resistance as previously explained.

It is to be understood that the arrangement of an actual station may be more or less of a modification of the arrangement described while conforming to it in that there will be one or more sections completely insulated from adjoining sections and each un-

der the control of a separate controller, whereby cars can be moved on one section without disturbing those on another.

When a car passes over the insulators I_9 or I_{11} , it leaves the control of the operator at the station and enters upon a series of sections I_9 — I_{11} — I_{12} , I_{12} — I_{13} , I_{13} — I_{14} and I_{14} — I_{15} , which I call "accelerating sections." The accelerating sections are normally connected to the positive main through successively less portions of the rheostat R_5 . The field conductor rail is likewise sub-divided, but as already explained, all of its sections, except in the case of sections that are under the control of controllers, are permanently connected to the positive main pm .

As the car advances over the accelerating sections, therefore, the resistance that was interposed in the armature circuit at starting is cut out step by step until at I_{15} the armature is receiving full voltage, the field F_1 being meanwhile separately excited to full strength, causing the car to be accelerated to full speed.

The section I_9 — I_{11} — I_{12} is connected to the positive main through the contactor K_1 , which has to do with the block system to be explained later. With this exception, the connections of the accelerating sections of the terminal station shown in Fig. 5 with the positive main are permanent.

The condition as to the proportioning of the accelerating sections which gives the most effective acceleration with a given number of sections is different from that obtaining in the case of braking, and can best be stated mathematically.

If S be the full speed of the car (corresponding with a speed of its motor armature which with field separately excited at constant strength produces a counter electro-motive-force equal to impressed electro-motive-force), s the speed at any instant, T the motor torque and R the total resistance of the armature circuit, then with the field separately excited to full strength:

$$T = \text{const. } \frac{(S-s)}{R}$$

The maximum positive accelerating torque, generally expressed in foot pounds, at the beginning of each section is limited either by the adhesion of the driving wheels or by the capacity of the motor, and is consequently the same for all of the sections. To procure suitable mean accelerating effect with a given number of sections, I prefer to make the mean accelerating effect upon each of them the same. This condition is secured by so proportioning the lengths of the sections and their associated armature circuit resistances that the accelerating effects at the initial ends of the sections are substantially equal and the accelerating effects at the terminations of the sections are

likewise substantially equal; and furthermore, the ratio of accelerating effect at the beginning of each section to the accelerating effect at the termination of each section is substantially the same for all sections with the exception of the last, in which case the same maximum accelerating effect is produced at the initial end of the last section, but the accelerating effect is reduced to zero as the car attains full speed. For instance, at the starting point of the car or train the resistance to be inserted in the armature circuit in order to give the maximum allowable accelerating torque is determined. With this factor known the rate of acceleration is determined. From this the length of the section necessary to insure at its end an accelerating effect which bears the desired ratio to the accelerating effect at its initial end is determined. The next step is the determination of the resistance to be inserted in the armature circuit for the next succeeding accelerating section. This, however, is a function of the speed at the end of the preceding section and is therefore determined in the same way as the corresponding resistance for the first section. This process is followed out for the desired number of sections, and we have the following relation:

$$\frac{T_2}{T_1} = \frac{T_4}{T_3} = \frac{T_6}{T_5}, \text{ etc.}$$

in which T_1 is the accelerating torque at the start, T_2 the torque at the end of the first accelerating section, T_3 the torque at the beginning of the second section, and T_4 the torque at the end of the second section, etc. Substituting for each torque value in the last equation its equivalent as given by a preceding equation as a relation between speed and resistance, we have the following:

$$\frac{S - s_1}{S - s_2} = \frac{S - s_3}{S - s_4}, \text{ etc.}$$

in which s_1, s_2 , etc., are the speeds at the beginning of the successive accelerating sections. This equation therefore expresses a condition of the most effective acceleration with a given number of sections.

At the intermediate station, (Fig. 8), approach, unloading and siding sections ($I_{28}-I_{29}, I_{29}-I_{30}, I_{30}-I_{31}$ and $I_{32}-I_{33}$), under control of the controllers C_8, C_{10}, C_{11} and C_{10} respectively, are found, but otherwise this station differs materially from the terminal station just described in ways that can best be explained in connection with the block system.

It has already been stated that the field conductor rail is divided into sections, each of which receives current through a series solenoid actuating a relay. For this purpose, among others, the positive main pm is carried along the line from one end to the

other and is everywhere indicated by the sign + (Figs. 5-10 inclusive).

The construction of these relays will be understood by reference to Figs. 38-43 inclusive.

The relay, as R_{21} , is arranged with its axis horizontal.

C_{12} is an iron core passing through the solenoids S_{11} and S_{12} , of which the former is the low resistance series solenoid through which the sections of the field conductor rail are supplied. When S_{11} is energized it draws the core C_{12} in the direction of the arrow in Fig. 38. W_3, W_4 are contacts between which passes the sleeve S_3 which is mounted upon the brass rod S_4 forming a continuation of the core C_{12} . The sleeve S_3 is metallic and in one position makes contact between the contacts W_3 . At the end which comes between these two contacts when the core is to the left, however, the sleeve S_3 is surfaced with an insulating material 100 and in this position the connection between the two contacts is interrupted. The sleeve S_3 is made free to slide upon the rod S_4 in order that it may lag back during the first half of the motion of the core C_{12} in the opposite direction to the arrow in Fig. 38 and compress the spring S_5 , which during the remainder of the movement re-expands and quickens the breaking of the circuit.

R_{21}, R_{24} , and R_{25} , Fig. 5, are relays of the type just described. Being represented diagrammatically, the contacts are shown between the solenoids instead of at one end, 100 but this does not change the principle of operation. When the solenoid nearest the contacts is energized, the connection between the contacts must be considered to be established. Relays of this type will be referred to hereinafter as single-ended relays.

R_{26}, R_{27}, R_{28} , etc., Fig. 6, are relays exactly similar to those just described except that the contact mechanism W_3, W_4 , at the one end is duplicated at the other end where the stationary contacts are W_6, W_7 . Relays of this type will be referred to as double-ended relays, and the contacts W_6 as "interrupting" contacts. Figs. 42 and 43 illustrate a modified form of relay, as R_{22} , intended to be operated with its axis vertical so that the weight of the core C_{12} and lead weight 101 in falling from position shown break the contact, thus dispensing with the shunt solenoid S_{12} . Relays of this type will be called gravity relays. R_{22} , Fig. 5, and R_{37} , Fig. 8 are of this type. These two relays are likewise shown diagrammatically and notwithstanding their position it must be understood that when the solenoid is energized, connection is established between the upper contacts; and in the case of relay R_{37} , and those like it, the lower contacts are connected when the solenoid is de-energized.

Referring again to Fig. 5 and taking the 13

relay R_{24} for illustration, it will be seen that there is a connection from the positive main through the series solenoid S_{11} to the field conductor rail section $I_{56}-I_{58}-I_{59}$, so that when there is a car upon this section the current passing to the field of its motor will excite the solenoid S_{11} and establish connection between the contacts W_3 .

It will be noticed that paralleling the positive main is a series of conductors 50 to 63, Fig. 5. If these be traced through it will be found that they connect through the electric lights L_1 , L_2 , L_3 , etc., at both the terminal and intermediate stations, with the negative main nm , so that if any one of these conductors be energized the corresponding lights will be lighted in both stations. The rheostats R_{19} and R_{20} regulate the voltage upon these lights.

In Fig. 5 a car is shown upon the section I_{59} , $I_{58}-I_{59}$ and connection is therefore established between the contacts W_3 of solenoid R_{24} . One of these contacts is connected to the positive main and the other to the conductor 50. Under these circumstances, therefore the lights L_1 will be lighted, indicating to the operators at both stations that there is a car or train on this section.

Similarly a car on any section between the stations will indicate its position.

When the car passes onto the section $I_{59}-I_{60}$, it operates the relay R_{25} in the manner described and lights the lights L_2 , through the conductor 51. But it will be observed that there is also a connection from the conductor 51 through the shunt solenoid S_{12} of the relay R_{24} to the negative main (or track rail), so that when the conductor 51 is energized the solenoid S_{12} is likewise energized. This operates the relay R_{24} to break the connection between the contacts W_3 and extinguishes the lights L_1 . If a car should break down in transit, therefore, the light of the last section that it passed onto will remain lighted even if it should cease to take current through the series solenoid of the corresponding relay. When there are sections of the line not provided with relays as is sometimes the case at the entrance to stations, the relay of the preceding section is of the gravity type as shown at R_{22} , Fig. 5, and R_{37} , Fig. 8, in order that it may reset itself or open its contacts after a car has passed off of the section with which it is associated.

We will now consider the block system which has already several times been referred to.

The function of the block system is to prevent collision with the following train in case (for instance) a train should stop for any reason between stations or be left standing upon a braking section.

This is accomplished by dividing the line into sections called "block sections", each of

which is capable of bringing a train to rest from full speed and re-starting it without injury, and the principle of operation is to maintain at all times a closed block section between trains in transit.

The method of bringing a train to rest in a block section is the same as that employed upon the braking section described, *i.e.*, to disconnect the armature conductor rail from the source of power and connect it to the track rail through a suitable resistance while the field is excited to full strength from the field conductor rail. Similarly the train is re-started by connecting the armature conductor rail to the source of power through a suitable resistance.

To make the operations of braking and accelerating more effective and thereby reduce the length of the block section, the latter is subdivided into a number of sections, some of which serve to cut out, step by step, the resistance in the armature circuit, when the armature is connected to the track rail in braking and others to cut out step by step the resistance interposed between the armature and the source of power in starting.

The operation of changing the connections to the armature conductor rail is performed by contactors similar to that shown in Figs. 34, 35, 36 and 37.

Referring to these figures, C_{13} and C_{14} are iron cores passing through the solenoids S_6 and S_7 respectively, and attached to the links L_{60} , L_{61} , which are of insulating material, to the arm A_2 . The arm A_2 is pivoted at P_7 , and carries at its ends the blades B_{51} , B_{61} , which are adapted to enter between and make contact with the contacts C_{15} or with similar contacts C_{16} at the opposite side.

The arm A_2 is electrically connected with the terminal P_1 , and the contacts C_{16} and C_{15} are respectively electrically connected with the terminal P_3 and with a similar terminal P_2 placed symmetrically opposite to P_3 .

The solenoids S_7 , S_6 have respectively electrical connection with the terminal P_6 and with a similar terminal (not shown) placed symmetrically opposite to P_9 , P_4 serving as a common return connection for both.

The arm A_2 and the frames F_3 carrying the contacts, etc., are insulated from the ironwork of the contactor and from each other by the insulators I_{105} .

When the solenoid S_6 is energized, the arm A_2 makes contact with the contacts C_{15} and thus establishes connection between P_1 and P_2 . When the solenoid S_7 is energized, connection is similarly established between P_1 and P_3 .

The blades B_5 , B_6 , are pivoted at P_8 and P_9 respectively and are normally held in the position shown by the springs S_9 and S_{10} respectively. When the arm A_2 starts to move the blade in contact lags behind, de-

flecting the spring, and when it finally disengages itself from the contacts the spring quickens the breaking of the circuit.

The contacts C_{15} are pressed together by the springs S_8 , which bear upon the disks D_1 , which in turn are soldered to the flexible connectors C_{17} and serve to convey the current from the contacts to the terminal P_2 . The disks D_1 , however, leave the contacts C_{15} free to rotate, and the lagging of the blade B_5 as above described tends to make them do so, thus presenting a fresh surface each time for the making and breaking of the circuit.

15. The flexible connector C_{18} serves to convey the current from each blade to the central frame and thence to the terminal P_1 .

The axes of the two contacts C_{15} are each set at a slight angle, 1 degree, for example, 20 with the horizontal and there is consequently an angle of 2 degrees between the two. This renders the entry of the blade B_5 smoother.

The inverted position of the contacting mechanism lends itself to the immersion of the mechanism in an oil bath which helps 25 to extinguish the arc and also improves the working and durability of the apparatus.

In Fig. 5 one of the contactors just described is indicated diagrammatically at K_1 . 30 The common terminal P_1 is here shown for clearness as two terminals, the identical function of which is, however, shown by their being connected together everywhere. It is to be at all times understood that the 35 contacts on the side of the contactor that is energized are connected together. Thus, in the position shown the solenoid S_7 is assumed to have been last energized and the terminals P_1 and P_3 are connected. In this position 40 it will be observed that the conductor rail section $I_9-I_{11}-I_{12}$ is short-circuited to the track while in the alternative position it is connected through the rheostat R_5 to the positive main.

45. Referring now to Fig. 7:

This figure illustrates a typical block section complete. It will be seen that as regards the armature conductor rail, it is subdivided into four sections. The first of 50 these, $I_{10}-I_{20}$ is intended to retard the car at need from full speed to half speed, the second, $I_{20}-I_{21}$, from half speed to quarter speed, and the third $I_{21}-I_{22}$, from quarter speed to rest. The car coming to rest near 55 the initial end of the section $I_{21}-I_{22}$, this section is also intended to accelerate it upon restarting to a speed approximating two-thirds of full speed (determined according to the law given above for accelerating sections). The section $I_{22}-I_{23}$ is intended to 60 further accelerate the car to five-sixths of full speed, at which the motor can safely receive the full voltage of the mains upon entering the next block section.

It will be seen that the field conductor rail 65 throughout this block section is sub-divided into five sections, which are therefore not co-terminous with or of the same lengths as the sections of the armature conductor rail. There must be at least one section of the 70 field conductor rail for each block section. Any further sub-division of this conductor rail is purely a matter of choice, and merely serves to enable the movement of the trains to be observed more closely at the stations. 75

Referring to the section $I_{10}-I_{20}$, it will be found that this receives current direct from the positive main through the contactor K_8 in one of its positions, while in the other position of this contactor it is connected 80 through the rheostat R_{10} to the track rail for braking.

Similarly the conductor rail section $I_{20}-I_{21}$ is connected to the track rail through the rheostat R_{10} (a less portion of it than before) in one position of the contactor K_{10} for braking. In the other position of K_{10} this section is connected to the common terminal P_1 of the contactor K_9 , which in one position connects it directly to the positive 90 main and in the other position connects it to the positive main through the rheostat R_{11} for accelerating. The two contactors K_9 and K_{10} in coöperation may therefore either short-circuit the section $I_{20}-I_{21}$ to the 95 track rail through a suitable resistance for braking, or connect it to the positive main through a suitable resistance for restarting the car, or connect it to the positive main direct for through cars. These three conditions are all that are required for the operation of closing or opening this part of the block system.

The conductor rail section $I_{21}-I_{22}$ is also provided with two contactors K_{11} and K_{12} , 105 which operate in the same way as the contactors K_9 and K_{10} , except that in this case the contactor K_{12} in one of its positions connects the section directly to the track rail with no resistance interposed.

The conductor rail section $I_{22}-I_{23}$ is provided with only one contactor K_{13} , which in one position connects the section to the positive main through the rheostat R_{12} (a less portion of it than in the case of the contactor K_{11}) and in the other position connects it to the positive main direct.

It will be observed that the section $I_{10}-I_{20}$ has only one contactor and no starting position because it is expected that the car will never come to rest on or have to be restarted from this section, while the section $I_{22}-I_{23}$ has only one contactor and no braking position because it is expected that the car will always come to rest before reaching this section.

It is also to be noticed that the successive sections are in the braking position by con-

nections to the track rail through progressively smaller resistances; or in the alternative starting position the successive sections are connected to the positive main likewise through progressively smaller resistances.

It will be obvious that the block section could be divided into a greater or less number of sections without affecting its principle of operation.

10 It should be noticed that at the beginning of the block section illustrated in Fig. 7 there is a reverse curve. This is assumed to be of too short a radius to be taken at full speed. Accordingly, provision is made 15 in the preceding block section, illustrated in Fig. 6, to retard the car to the safe speed before it reaches this curve. For this purpose the last conductor rail section of the block section, $I_{18}-I_{19}$, is normally short-circuited through the rheostat R_6 , controlled by contactor K_7 . In other respects the operation of this block section is the same as that described.

Returning to Fig. 7:

25 The closing and opening of this block section is effected as follows:

It will be found that the S_7 solenoids of Fig. 7, which in every case operate the contactors to close the block section, are all 30 connected to the conductor 62, while the other or common terminals of these solenoids are connected to the track rail or negative main. If, therefore, the conductor 62 be energized, the entire block section will 35 be closed. This is the position in which the contactors are shown in the figure. In Figs. 14, 15 and 16, the contactors of this block section are for clearness shown diagrammatically by themselves, and Fig. 14 40 also illustrates the closed section.

The solenoids S_6 of the contactors K_{10} and K_{12} will be found to be connected to the conductor 64, so that if this conductor be energized these contactors will be thrown 45 into the normal or opening position. If the remaining contactors of this block section then remain as they were, viz., in the closing position, the sections $I_{20}-I_{21}$ and $I_{21}-I_{22}$ will be found to be connected to the 50 positive main through the rheostats R_{11} and R_{12} respectively, which are calculated to give the starting voltage. The section $I_{22}-I_{23}$ remains at the accelerating position. The whole block section is therefore in a 55 position to restart the car from any point on $I_{20}-I_{21}$ or $I_{21}-I_{22}$ and accelerate it to the speed at which it may safely pass on to the next block section and receive full voltage. This (the starting) position of the contactors of this block section is illustrated 60 in Fig. 15.

It will be seen, however, that the conductor 64 is also connected through the interrupting contacts W_6 , in series, of the 65 double-ended relays R_{31} , R_{32} , R_{33} , R_{34} , and

R_{35} to the S_6 solenoids of the remaining contactors of this block section, viz., K_8 , K_9 , K_{11} and K_{13} , through the conductor 64^a. If, therefore, there is no interruption in the circuit 64^a at any of these relay contacts 70 W_6 the contactors K_8 , K_9 , K_{11} and K_{13} will likewise be thrown into the open block position when the conductor 64 is energized. This will result in supplying full voltage to all the sections of this block section, or, 75 in other words, in throwing it completely open. This position of the contactors is illustrated in Fig. 16.

The connection from the conductor 64 through the interrupting contacts W_6 of the 80 relays R_{31} to R_{35} inclusive and conductor 64^a will be unbroken if there is no car upon this block section, but if there is a car anywhere upon it the current to its field will cause the relay through which it passes to 85 make connection between its left-hand contacts W_3 and break the connection at its interrupting contacts W_6 thus breaking the connection to the S_6 solenoids of the contactors K_8 , K_9 , K_{11} and K_{13} preventing 90 them from operating.

To recapitulate therefore, this block section is closed when the conductor 62 is energized and when the conductor 64 is energized it is thrown either into the starting 95 position or into the open position, depending upon whether there is a car upon this block section at the moment.

The connections made by the contactors of the first block section illustrated in Fig. 100 6 in each of their several positions are clearly shown in Figs. 11, 12 and 13. They are the same as for the second block section except as regards the last contactor in the series whose positions differ from those of 105 the corresponding contactor of the second block section for the reasons already given, i. e., the presence of a sharp curve in the section immediately following.

It has been stated that the principle of operation of the block system is to maintain at 110 all times a closed block section between trains during their transit. This is carried out by causing each train as it enters a new block section to close the block section that it has just left and, if the second block section behind it was previously closed, to open it.

When the operator at the terminal station, Fig. 5, wishes to despatch a car standing upon the loading section, I_8-I_9 , he 115 moves the controller C_5 manually, in a manner to be hereinafter described, into the starting position. The car at once leaves the loading section and enters upon the exit section, $I_9-I_{11}-I_{12}$. In so doing, the current 120 passing to the field F_1 of the motor operates the relay R_{24} and energizes the conductor 50, lighting the lights L_1 in both stations. Proceeding, the car enters the section $I_{12}-I_{13}$. This energizes the S_{11} solenoid of 125

130

the relay R_{25} , thus energizing conductor 51 and lighting the lights L_2 and returns the relay R_{24} to its normal position, extinguishing the lights L_1 . But it will be noticed that there is also a connection from the conductor 51 to the S_7 solenoid of the contactor K_1 , so that when this conductor is energized the contactor K_1 is thrown into the closing position, connecting the conductor rail section 10 $I_9-I_{11}-I_{12}$ directly to the track rail. If a second train is now despatched it will come to rest by braking in the exit section.

Continuing its course, the train passes over the sections $I_{12}-I_{13}$, $I_{13}-I_{14}$ and 15 $I_{14}-I_{15}$, by which time it has been accelerated to full speed. The train now enters upon the first block section $I_{15}-I_{19}$, Fig. 6, and passes over and beyond it, lighting and extinguishing successively the lights L_3 , L_4 , 20 L_5 , L_6 and L_7 , the exit section remaining closed meanwhile.

Upon passing I_{19} , Figs. 6 and 7, the train enters upon the second block section, and in so doing it operates the relay R_{21} , Fig. 7. 25 This energizes the conductor 57, extinguishing the lights L_7 and lighting the lights L_8 . But the conductor 57 will be found to have connection with all the S_7 or block closing solenoids of all the contactors, K_2 , K_3 , K_4 , 30 K_5 , K_6 , of the first block section, as well as with the S_6 or closing solenoid of contactor K_7 and the S_6 or opening solenoid of the contactor K_1 . When the conductor 57 is energized, therefore, the exit section will be 35 opened and the entire first block section simultaneously closed.

Similarly, upon passing I_{23} , Figs. 7 and 8, the conductor 62 is energized by relay R_{26} whose solenoid S_{11} is energized through 40 solenoid 49. It will be remembered that this closes the entire second block section, $I_{19}-I_{23}$, Fig. 7. But it will also be found that the conductor 62 has a connection with the S_6 or opening solenoids of the first block 45 section (Fig. 6), except in the case of contactor K_7 whose solenoid S_7 connects with conductor 62. Thus, as there is no car on the first block section at the moment, it will be opened simultaneously with the closing 50 of the second block section.

We now come to the third block section, which as already stated, includes the intermediate station. (Fig. 8).

When the switch points P_{10} , P_{11} , which 55 are worked simultaneously in a manner to be described hereinafter, are in the "past" position, *i. e.*, for directing the train past the station, the third block section automatically, in a manner that will be explained 60 hereinafter, takes its place in the series of block sections, of which the fourth and fifth block sections illustrated in part in Figs. 9 and 10 respectively are a continuation. Under these circumstances the third block 65 section operates exactly like any other block

section, closing each time a train passes off it and opening when the train has traversed the next block section.

When the switch points P_{10} , P_{11} , are thrown into the station position, however, 70 the third block section, in a manner to be explained, automatically adapts itself to the station requirements, that portion to the left of the switch points P_{10} becoming a braking section under control of the operator in the station, while the portion following the switch points P_{11} becomes an accelerating section, the approach, unloading, loading, siding and exit sections being found in the 75 normal relation to each other.

In Fig. 8 the switch points P_{10} , P_{11} , are assumed to be in the station position and a car X_1 , is shown in the position of having just come to rest upon the braking section. In conformity with this circumstance, the 80 first block section behind it (Fig. 7) is closed, and the second one behind it (Fig. 6) is open.

A car X_2 is shown in transit on the first block section (Fig. 6) and in consequence 90 the exit section at the terminal station (Fig. 5) is shown closed. A car X_3 is shown held up upon this exit section.

Under these conditions, if the car X_1 remains in the position shown, the car X_2 will 95 presently come to rest in the second block section (Fig. 7). In entering this section car X_2 will close the first block section (Fig. 6) and open the exit section (Fig. 5) releasing the car X_3 . The car X_3 will then advance and come to rest upon the first block section (Fig. 6). If a fourth car is now despatched it will be held up in the exit section. Thus all the block sections will be occupied and no further cars can be despatched until the car X_1 is moved.

When the car X_1 is brought into the intermediate station (Fig. 8) X_2 and X_3 will each move up one block section, or if the switch points P_{10} , P_{11} , are moved to the 110 "past" position they will pass the intermediate station at full speed with two block sections separating them, one of these two block sections always closed.

It will be observed that the third or intermediate station block section (Fig. 8) has sub-divisions corresponding to those of the braking section and accelerating sections of the terminal stations, and these are considerably more numerous than are the sections 120 of an ordinary block section. The principle of operation, however, is precisely the same. Each section has at least one contactor and those sections of the braking section upon which the trains are expected to stop are 125 provided with two contactors each, giving the braking, starting and through positions desired in the way that has already been explained. Thus K_{14} belongs to section $I_{23}-I_{24}$, which retards from 30 to 15 M. P. H.; 130

K₁₅ belongs to the section I₂₄—I₂₅, which is the equalizing section connected to positive main pm through resistance R₁₅; K₁₆ and K₁₇ belong to the section I₂₅—I₂₆, which retards from 10 to 5 M. P. H.; K₁₈ and K₁₉ belong to section I₂₆—I₂₇, which retards from 5 to 2½ M. P. H.; and K₂₀ and K₂₁ belong to section I₂₇—I₂₈—I₃₄, which brings the car or train to rest. Like-wise, K₂₄, K₂₅ and K₂₆ belong to the accelerating sections I₃₅—I₃₆—I₃₇; I₃₇—I₃₈ and I₃₈—I₃₉, respectively, while K₂₂ belongs to the section that extends between the switch points and K₂₃ belongs to the exit section.

It has been stated that when the switch points P₁₀, P₁₁, are in the station position the braking section is under control of the operator in the station. This is by means of the controller C₆. As the control of a block section is effected by means of two conductors only, connected the one to all the S₆ solenoids in parallel and the other to all the S₇ solenoids in parallel, C₆ has only three fingers, one of which, 38, communicates with the positive main. It will be seen that the finger 39 is connected to the finger 44 of controller C₇ and thence through the drum to the finger 45, whence the connection, branching at 82, 83, 86, etc., is to the S₇ solenoids of all the contactors belonging to this section. With the controllers C₆ and C₇ in the position shown, therefore, all the contactors of the braking section will be thrown into the braking position and all those of the accelerating sections into the accelerating position. Similarly, the finger 40 is connected to the finger 43 of the controller C₇ and thence through the drum to the finger 47, whence the connection is to the S₆ solenoids of the contactors K₁₇, K₁₈, and K₂₁, these being the contactors of the three double sets which, it will be remembered must alone be operated to throw the braking section into the starting position. (If the remaining contactors were operated at the same time, the through and not the starting position would result.) The contactors of the accelerating section, when once thrown into the accelerating position, are for obvious reasons independent of the controller C₆ and remain in that position so long as the switch points P₁₀, P₁₁ are in the station position.

Although Fig. 8 shows the controller C₆ and the contactors in the braking position, the connection within this controller is shown again in Fig. 30 to facilitate comparison with the connection made in the alternative or starting position shown in Fig. 31. Likewise, the connections made by the contactors in the braking position are shown again in Fig. 17 to facilitate comparison with the connections made in the starting position shown in Fig. 18.

It has been shown that the connections by which the controller C₆ operates the braking section are carried through the controller C₇ and are dependent upon connection being established in the drum of the latter between the fingers 44 and 45 and 43 and 47 respectively, as is the case in Fig. 8 and also in Fig. 32. In Fig. 33, however, which shows the alternative position of the controller C₇, these connections are interrupted. But the controller C₇ is operated simultaneously with the switch points P₁₀, P₁₁ and the position shown in Fig. 33 is the "past" position. Hence, in the past position the control of the braking section is taken out of the hands of the operator.

When the switch points have been in the station position and are returned to the past position, this whole block section must automatically assume a position appropriate to the circumstances. That is to say, if there is a train at the moment upon the fourth block section, then the third block section must be closed; otherwise it must be open. To effect this automatic control I provide the relay R₄₂, which I call a "master relay." This relay is double-ended and has no series solenoid, but is equipped with two shunt solenoids adapted to work upon the full voltage of the mains. It will be seen that the conductor 69, (Figs. 8 and 9), which is the one that is energized when the train enters the fourth block section, connects through one of these solenoids, S₂₄, to the negative main, while the conductor 74 (Figs. 8, 9 and 10), which is the one that is energized when the train enters upon the fifth block section, connects through the other solenoid, S₂₅, also to the negative main. Hence, as long as there is a train on the fourth block section, the contacts W₅ will be connected together, but when the train has passed to the fifth block section it will set the relay R₄₂ in the other position and leave it so, with the contacts W₄ connected together.

Now, it will be found that the contacts W₅ connect from the positive main to the finger 42 of the controller C₇, and when this controller is in the "past" position, as in Fig. 33, the finger 42 is connected through the drum to the fingers 45 and 46. But it has already been shown that the finger 45 communicates with the S₇ solenoids of all the contactors of the third block section and, when energized, throws this section into the closed position, and the finger 46 will be found to communicate with the conductor 64, which, it will be remembered, opens the second block section. Hence, with the controller C₇ in the "past" position, the third block section is closed and the second block section is opened whenever a car enters the fourth block section, which is in accordance

with the established principle upon which the block system operates.

The contacts W_4 connect in a similar manner to the finger 41 of the controller C_7 , and 5 when this controller is in the "past" position, as will be seen from Fig. 33, the finger 41 is connected through the drum to the fingers 47 and 48. But the finger 47 has already been shown to communicate with S_6 sole- 10 noids of the contactors K_{17} , K_{19} and K_{21} , which if operated alone would give the starting position, and the finger 48 will be found to connect in series through the "interrupting" contacts, W_6 , of all the relays associated 15 with this block section, viz., R_{36} , R_{37} , R_{28} and R_{43} , and thence to the S_6 solenoids of the remaining contactors. When energized together, therefore, the fingers 47 and 48 throw the whole block section into either the starting 20 or the through position (depending upon whether there is a car upon it at the moment or not). Hence, with the controller C_7 in the "past" position, the third block section is opened by a car passing on to the fifth block 25 section, which again is in accordance with the principle of the operation of the block system.

The master relay R_{42} , remains in the position in which it was last set, even after its 30 solenoids cease to be energized. Hence, if, for example, the third block section is in the braking position when the switch points are thrown into the "past" position and the circumstances are such that it should be 35 open (*i. e.*, there is no car on the fourth block section) it will be automatically opened by the master relay R_{42} .

When there is a car on the third block section, the second block section will, of course, 40 be closed, and if this car passes off via the fourth block section the second block section will be opened in the normal manner. But if the car passes off the third block section by entering the intermediate station, this 45 operation will not take place. Consequently it is necessary to provide means of opening the second block section when the car enters the intermediate station.

This is done by means of the special relay 50 R_{39} , Fig. 8. This relay is of the standard type, having a series solenoid S_{28} and a shunt solenoid S_{27} . The connection to the field conductor rail section $I_{73}-I_{74}$ is through the series solenoid S_{28} , and when a car 55 passes into this section it causes contact to be made between the contacts W_8 . One of the contacts W_8 has a connection through the points 91 and 82 with the finger 45 of the controller C_7 , and the other contact 60 W_8 is connected through the point 89 to the conductor 64, which it will be remembered opens the second block section.

The operation, then, is as follows:

When a car in entering the intermediate

station passes the section $I_{73}-I_{74}$, it makes 65 contact between the finger 45 and the conductor 64. But in starting the car upon the braking section the controller C_6 was necessarily set in the starting position. In this position the finger 45 is not energized 70 and the second block section remains closed. But if the controller C_6 be then moved back to the braking position, the finger 45, which it will be remembered, is in the circuit for setting the contactors in the braking position, 75 will be energized and with it the conductor 64, and the second block section will be opened.

The relay R_{39} is returned to its normal position by the next car arriving upon the section $I_{70}-I_{71}$, through connection between its shunt solenoid S_{27} and the conductor 62.

Returning to Fig. 8, magnet 90 may be found beneath the controller C_6 , and it will be seen that it has connection with the conductor 63, which is energized by the relay R_{37} whenever there is a car in the section $I_{71}-I_{72}-I_{73}$. When the controller C_6 is moved to braking position it is locked in that position and remains so locked so 90 long as magnet 90 is deenergized; when magnet 90 is energized it releases the controller C_6 .

To recapitulate, therefore, when a car enters the intermediate station the block section is not released until the braking section is reset in the braking position, and when so set it is locked in that position until the next car unlocks it. Thus, when the switch points are in the station position it is 100 impossible to have a car arrive on the braking section when it is in any position but the braking position.

In Fig. 5, the relay R_{23} performs a function similar to that of the relay R_{39} just 105 described, *i. e.*, it opens the block section preceding the terminal station when the controller C_1 is in the braking position, the finger 28 of the controller C_1 supplying current to the contacts of the relay R_{23} only when the controller C_1 is in the braking position. The magnet 29 performs a function similar to that of the magnet 90, *i. e.*, it unlocks the controller C_1 when there is a 110 car on the section $I_{52}-I_{53}$.

I do not wish to be understood as limiting my invention to the form of system and apparatus herein disclosed, for it is evident that the principle of my invention may be practised with other arrangements and apparatus.

It is to be further understood that my invention is not limited to the employment of a shunt wound motor except where so specified in the claims, for while a shunt wound motor is preferred, in some applications of my invention other types of motor may be employed.

This application is a division from my prior application Serial Number 693,973, filed April 29, 1912.

What I claim is:

5. 1. In an electric railway system, a car, a shunt motor thereon for driving the same, a contact conductor extending along the trackway for supplying current to the shunt field of said motor, a second contact conductor extending along the trackway for supplying current to the armature of said motor, a common return contact conductor, permanent connections on said car between the motor armature and field and said contact conductors, 10 means subdividing said armature contact conductor into sections, and means for impressing upon different of said sections different voltages, whereby the speed of the car is changed.
- 20 2. In an electric railway system, a car, a shunt wound motor thereon for driving the same, a contact conductor extending along the trackway for supplying current to the shunt field of said motor, a second contact conductor extending along the trackway for supplying current to the armature of said motor, a return contact conductor common to said shunt field and armature of said motor, means sub-dividing said armature contact conductor, a source of current, resistances, the sub-divisions of said armature contact conductor comprised in a block section and connected with said source of current through resistances of progressively diminishing values, a contactor controlling the connections between said contact conductor sub-divisions, and means responsive to current of another block section controlling said contactor.
- 30 3. In an electric railway system, a car, a shunt wound motor thereon for driving the same, a contact conductor extending along the trackway for supplying current to the shunt field of said motor, a second contact conductor extending along said trackway for supplying current to the armature of said motor, and means sub-dividing said armature contact conductor, the sub-divisions of said armature contact conductor subjected 35 to different voltages, and automatic contactor mechanism controlled by current delivered to the shunt field of a motor of another car controlling the connections to said subdivisions of said armature contact conductor.
- 45 4. In an electric railway system, a car, a shunt wound motor thereon for driving the same, a contact conductor extending along the trackway for supplying current to the shunt field of said motor, a second contact conductor extending along said trackway for supplying current to the armature of said motor, means sub-dividing said armature contact conductor, means for subjecting 50 the sub-divisions of said armature contact conductor to progressively increasing voltages, and electro-magnetic switching means controlling the circuits of said sub-divisions of said armature contact conductor.
5. In an electric railway system, a car, a shunt wound motor thereon for driving the same, a contact conductor extending along the trackway for supplying current to the shunt field of said motor, a second contact conductor extending along said trackway 55 for supplying current to the armature of said motor, means sub-dividing said armature contact conductor, the sub-divisions of said armature contact conductor subjected to different voltages, a return contact conductor common to said shunt field and said armature of said motor, and means responsive to current delivered to another motor controlling the circuits of said sub-divisions of armature contacting conductor.
6. In an electric railway system, a car, a shunt wound motor thereon for driving the same, a contact conductor extending along the trackway for supplying current to the shunt field of said motor, a second contact 60 conductor extending along said trackway for supplying current to the armature of said motor, means sub-dividing said armature contact conductor, the sub-divisions of said armature contact conductor subjected to progressively increasing voltages, a return contact conductor common to said shunt field and said armature of said motor, electro-magnetic switching means controlling the circuits of said sub-divisions of 65 armature contact conductor, and a relay responsive to current delivered to another motor controlling said last named means.
7. In an electric railway system, a car, a motor thereon for driving the same, a contact conductor extending along the trackway for supplying current to said motor, means sub-dividing said contact conductor into a series of subdivisions, means for subjecting the successive sub-divisions of said contact conductor to progressively increasing voltages, whereby said car in passing over said sub-divisions is accelerated, the voltages impressed upon successive subdivisions of said contact conductor and the 70 lengths of said sub-divisions of said contact conductor being so proportioned that the ratio of the full speed of the car minus the speed of the car at the initial end of a sub-division to the full speed of the car minus the speed of the car at the initial end of the next sub-division is constant for the series of sub-divisions.
8. In an electric railway system, a car, a shunt wound motor thereon for driving the same, a contact conductor extending along the trackway for supplying current to the shunt field of said motor, a second contact 75

conductor extending along the trackway for normally supplying current to the armature of said motor, a return contact conductor common to the shunt field and armature of said motor, and means for sub-dividing said armature contact conductor, sub-divisions of said armature contact conductor connected to said return contact conductor through paths of progressively decreasing resistances, whereby the car progressively diminishes in speed.

9. In an electric railway system, a car, a shunt wound motor thereon for driving the same, a contact conductor extending along the trackway for supplying current to the shunt field of said motor, a second contact conductor extending along said trackway for normally supplying current to the armature of said motor, a return contact conductor common to the shunt field and armature of said motor, means for sub-dividing said armature contact conductor, resistances, the sub-divisions of said armature contact conductor connected to said return contact conductor through progressively diminishing resistances, electro-magnetic switching means controlling the circuits through said resistances, and means responsive to current supplied to another motor controlling said last named means.

10. In an electric railway system, a source of current, a car, a motor thereon, a contact conductor extending along the trackway for connecting the field of said motor to said source of current, whereby the motor field is excited to full strength, a second contact conductor extending along the trackway for supplying current from said source to the armature of said motor, a return contact conductor common to said motor field and motor armature, permanent connections on said car between the motor armature and field and said contact conductors and means for sub-dividing said armature contact conductor, sub-divisions of said armature contact conductor isolated from said source of current and connected to said common return contact conductor through paths of different resistances.

11. In an electric railway system, a source of current, a car, a motor thereon, a contact conductor extending along the trackway for connecting the field of said motor to said source of current, whereby the motor field is excited to full strength, a second contact conductor extending along the trackway for supplying current from said source to the armature of said motor, a return contact conductor, means sub-dividing said armature contact conductor, resistances, sub-divisions of said armature contact conductor isolated from said source of current and connected to said return contact conductor through progressively diminishing resistances, elec-

tro-magnetic switching means for connecting said sub-divisions of armature contact conductor either to said source of current or through said resistances, said electro-magnetic switching means controlled by current of a motor of another car.

12. In an electric railway system, a car, a motor thereon, a pair of contact conductors extending along the trackway and connected with the terminals of the armature of said motor, means sub-dividing one of said contact conductors, sub-divisions of said contact conductor connected to said other contact conductor through progressively diminishing resistances, whereby the car in passing over said sub-divisions is retarded, said resistances and the lengths of said sub-divisions being so proportioned that the ratio of reduction of speed of the car on successive sub-divisions is constant.

13. In an electric railway system, a source of current, a car, a motor thereon for driving the same, contact conductors extending along the trackway and connected to the motor terminals, means for sub-dividing one of said contact conductors, two sub-divisions of said contact conductor connected to another of said contact conductors, and a third sub-division located between said two sub-divisions connected to one terminal of said source of current whose other terminal is connected to the other contact conductor.

14. In an electric railway system, a source of current, a car, a motor thereon, a contact conductor extending along the trackway for exciting the field of said motor, a second contact conductor extending along the trackway for normally supplying current to the armature of said motor, a return contact conductor common to said field and armature of said motor, means for sub-dividing said armature contact conductor, two of said sub-divisions connected to said return contact conductor, and a third sub-division of said armature contact conductor located between said two sub-divisions and connected to said source of current.

15. In an electric railway system, a source of current, a car, a motor thereon, a contact conductor extending along the trackway for supplying current to the field of said motor, a second contact conductor extending along the trackway for normally supplying current to the armature of said motor, a return contact conductor, means for sub-dividing said armature contact conductor, two sub-divisions of said armature contact conductor connected to said return contact conductor, a resistance, and a third sub-division of said armature contact conductor located between said two sub-divisions and connected to said source of current through said resistance.

16. In an electric railway system, a car,

- a motor thereon for driving the same, a source of current, and automatic means controlled by another car for isolating the motor of said first named car from said 5 source of current and for short circuiting said motor, whereby said car is braked.
17. In an electric railway system, cars, motors thereon for driving the same, a contact conductor extending along the path of 10 travel of said cars for delivering current to said motors and divided into independent sections, a return contact conductor, a source of current, and automatic means controlled by current delivered to the motor of one car 15 for isolating a section of said contact conductor from said source of current and connecting it to the return contact conductor, whereby a car on said section is braked.
18. In an electric railway system, cars, 20 motors thereon for driving the same, a source of current, motor armature and motor field contact conductors extending along the path of travel of said cars, means dividing said contact conductors into independent 25 sections, and automatic means controlled by the current delivered to the field of a car on a section for isolating the armature contact conductor of another section from said source of current, whereby the speed of a 30 car on said other section diminishes.
19. In an electric railway system, a car, a motor thereon, a contact conductor extending along the trackway and divided into block sections, automatic means associated 35 with each block section for bringing said car to rest and for restarting said car, said means when restarting the car applying to the motor thereof voltage correlated to the speed of the car, and means controlled by 40 said car for automatically putting the block section in the rear in condition for bringing a car to rest.
20. In an electric railway system, a car, a motor thereon, a contact conductor extending 45 along the trackway and divided into block sections, automatic means associated with each block section for bringing said car to rest and for restarting said car, said means when restarting the car applying to the motor thereof voltage correlated to the speed of the car, and means controlled by 50 said car for automatically putting the block section in the rear in condition for bringing a car to rest and for putting the 55 second block section in the rear in condition for restarting a car and thereafter increasing its speed.
21. In an electric railway system, a car, a motor thereon, a sub-divided contact conductor 60 extending along the trackway for supplying current to said motor, a return contact conductor, a contactor, a source of current, said contactor in one position connecting a sub-division of said contact conductor with said source of current and in another position connecting said sub-division of said contact conductor with said return conductor, and means responsive to current in another sub-division of contact conductor controlling said contactor. 65
22. In an electric railway system, a car, a motor thereon, a sub-divided contact conductor extending along the trackway for supplying current to said motor, a return contact conductor, a contactor, a source of 70 current, said contactor in one position connecting a sub-division of said contact conductor with said source of current and in another position connecting said sub-division of contact conductor with said return conductor, and means responsive to current delivered to a car on the second sub-division ahead for moving said contactor to said first named position. 75
23. In an electric railway system, a car, a motor thereon, a sub-divided contact conductor extending along the trackway for supplying current to said motor, a return contact conductor, a contactor, a source of 80 current, said contactor in one position connecting a sub-division of said contact conductor with said source of current and in another position connecting said sub-division of contact conductor with said return conductor, and means responsive to current delivered to a car on the second sub-division ahead for moving said contactor to said first named position. 85
24. In an electric railway system, a contact conductor extending along the trackway and separated into sub-divisions, a source of current, a contactor for each sub-division controlling supply of current from 90 said source of current, said contactors in one position connecting a plurality of sub-divisions directly to said source of current, a return contact conductor, said contactors in another position connecting said sub-divisions to said return conductor through resistances. 95
25. In an electric railway system, a contact conductor extending along the trackway and separated into sub-divisions, a source of current, a contactor for each sub-division controlling supply of current from 100 said source of current, said contactors in one position connecting a plurality of sub-divisions directly to said source of current, a return contact conductor, said contactors in another position connecting said sub-divisions to said return conductor through resistances. 105
26. In an electric railway system, a contact conductor extending along the trackway and separated into sub-divisions, a source of current, a contactor for each sub-division controlling supply of current from 110 115 120 125

- 5 said source of current, said contactors in one position connecting a plurality of sub-divisions directly to said source of current, a return contact conductor, said contactors in another position connecting a sub-division to said return conductor through a resistance and means for subjecting one or more of the following sub-divisions to progressively increasing voltages.
- 10 27. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting a plurality of sub-divisions to said return conductor through resistances diminishing progressively in the direction of travel and means for subjecting one or more of the following sub-divisions to progressively increasing voltages.
- 15 28. In an electric railway system, a car, a motor thereon, a sub-divided contact conductor extending along the trackway for supplying current to said motor, a return contact conductor, a source of current, a contactor in one position connecting a sub-division of said contact conductor to said return conductor, a second contactor, said first contactor in another position connecting said sub-division with said second contactor, said second contactor in one position connecting said sub-division directly to said source of current and in another position controlling means for subjecting said sub-division to reduced voltage.
- 20 29. In an electric railway system, a car, a motor thereon, a contact conductor extending along the trackway for supplying current to the armature of said motor, said armature contact conductor divided into block sections, means associated with each block section for causing a car to come to rest thereon, means associated with each block section for restarting a car thereon, a second contact conductor for supplying current to the field of said motor, said field contact conductor divided into sections corresponding with said block sections of said armature contact conductor, and a relay for each block section operated by the current flowing from the corresponding section of field contact conductor to the field of said motor, each of said relays when energized placing the first block section in the rear in condition to bring a car to rest.
- 25 30. In an electric railway system, a car, a motor thereon, a contact conductor extending along the trackway for supplying current to the armature of said motor, said armature contact conductor divided into block sections, means associated with each block section for causing a car to come to rest thereon, means associated with each block section for restarting a car thereon, a second contact conductor for supplying current to the field of said motor, said field contact conductor divided into sections corresponding with said block sections of said armature contact conductor, and a relay for each block section operated by the current flowing from the corresponding section of field contact conductor to the field of said motor, each of said relays when energized placing the first block section in the rear in condition to bring a car to rest.
- 30 31. In an electric railway system, a source of current, electric motor cars, a contact conductor extending along the trackway for supplying current to the car motors, said contact conductor divided into sub-divided block sections, contactors, a return contact conductor, resistances, a plurality of said sub-divisions of said contact conductor controlled by contactors which in one position subject said sub-divisions to the full voltage of said source of current and in another position connect said sub-divisions to said return contact conductor through resistances diminishing in value in the direction of travel of said motor cars, a plurality of succeeding sub-divisions of said contact conductor controlled by contactors which in one position connect said succeeding sub-divisions to said return contact conductor through resistances diminishing in value in the direction of travel of said cars and in another position connecting said succeeding sub-divisions to said return contact conductor through resistances diminishing in value in the direction of travel of said cars and in another position connecting said succeeding sub-divisions to a second set of contactors, said last named contactors in one position subjecting said succeeding sub-divisions to the full voltage of said source of current and in another position subjecting said succeeding sub-divisions to voltages less than the full voltage of said source of current, said voltages increasing progressively in the direction of motion of said motor cars, and a plurality of succeeding sub-divisions of said contact conductor controlled by contactors which in one position subject said last named sub-divisions to the full voltage of said source of current and in another position subject said sub-divisions to voltage less than the full voltage of said source of current, said voltages increasing progressively in the direction of travel of said motor cars.
- 35 32. In an electric railway system, a source of current, a car, a motor thereon, a sub-divided contact conductor for supplying current from said source to the armature of said motor, a second sub-divided contact con- 125

tor for supplying current to the field of said motor, a return contact conductor, contactors, a contactor normally connecting a section of said armature contact conductor to a 5 second of said contactors and in another position connecting said section of armature contact conductor to said return contact conductor, said second contactor in normal position subjecting said section of said armature contact conductor to the full voltage of 10 said source of current and in another position subjecting said section of armature contactor to reduced voltage, a relay controlled by the current supplied by said field contact conductor to the motor field, a normally closed circuit, said relay when energized breaking said normally closed circuit, a second similar relay operating similarly in 15 connection with a succeeding section of said field contact conductor, a third similar relay operating similarly in connection with a second succeeding section of said field contact conductor, said second relay when energized causing both said contactors to move 20 to their second named positions, said third relay when energized setting said first contactor positively in its normal position, said third relay simultaneously either completing or 25 not completing a circuit to similarly set said second contactor in its normal position according as the normally closed circuit controlled by said first relay is closed or open.

33. In an electric railway system, the combination with cars, of motors thereon for driving the same, a contact conductor extending along the path of travel of said cars, said contact conductor divided into block sections, means for dividing each block 35 section into a plurality of sub-section, a return contact conductor, resistances, and electromagnetic switching mechanism controlled by current delivered to a motor of a car on another block section for bringing 40 said sub-sections of contact conductor into communication with said return conductor through said resistances, said resistances diminishing in magnitude in the direction of travel of said cars, whereby a car traversing 45 said sub-sections of contact conductor is braked.

34. In an electric railway system, a car, a motor thereon for driving the same, a curve in the trackway, and automatic means for 55 retarding a car as it approaches said curve comprising a resistance of constant value and means for short circuiting the motor armature through said resistance.

35. In an electric railway system, a car, a 60 motor thereon, a contact conductor extending along the trackway for supplying current to the field of said motor, a second contact conductor extending along said trackway for supplying current to the armature

of said motor, a return contact conductor 65 common to both field and armature of said motor, said armature contact conductor sectioned in advance of a curve in the trackway, and a resistance of constant value connecting said section of armature contact 70 conductor to said return contact conductor.

36. In an electric railway system, a car, a motor thereon, motor field and armature contact conductors extending along the path of travel of said car and divided into block 75 sections, means associated with each block section for bringing said car to rest and for restarting said car, and means controlled by motor field current from a section of said contact conductor for automatically putting 80 the block section in the rear in condition for bringing a car to rest.

37. In an electric railway system, a car, a motor thereon, motor field and armature contact conductors extending along the path 85 of travel of said car and divided into block sections, means associated with each block section for bringing said car to rest and for re-starting said car, and means controlled by motor field current from a section of said 90 contact conductor for automatically putting the block section in the rear in condition for bringing a car to rest, and for putting the second block section in the rear in condition for re-starting a car. 95

38. In an electric railway system, a car, a motor thereon, a sub-divided contact conductor extending along the trackway for supplying current to said motor, a return contact conductor, a contactor, a source of current, said contactor in one position connecting a sub-division of said contact conductor with said source of current and in another position connecting said sub-division of contact conductor with said return conductor, and means responsive to current delivered to the field of a motor on a car on a sub-division 100 ahead for controlling said contactor. 105

39. In an electric railway system, a car, a motor thereon, a sub-divided contact conductor 110 extending along the trackway for supplying current to said motor, a return contact conductor, a contactor, a source of current, said contactor in one position connecting a sub-division of said contact conductor with said source of current and in another position connecting said sub-division of contact conductor with said return conductor, and a relay responsive to field current 115 of a car motor, for controlling said contactor. 120

40. In an electric railway system, a car, a motor thereon, a sub-divided contact conductor 125 extending along the trackway for supplying current to said motor, a return contact conductor, a contactor, a source of current, said contactor in one position connecting a sub-division of said contact con-

5 ductor with said source of current and in another position connecting said sub-division of contact conductor with said return conductor, a relay responsive to current delivered to the field of a motor on a car on a sub-division ahead controlling said contactor to take said second position, and a relay responsive to current delivered to the field of a motor on a car on a second sub-division ahead controlling said contactor to take said first named position.

10 41. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting said sub-divisions to said return conductor through resistances, and a relay responsive to current delivered to the motor of a car on a sub-division ahead controlling said contactors.

15 42. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting sub-divisions to said return conductor through resistances, and a relay responsive to current delivered to the field of a motor on a car on a sub-division ahead controlling said contactors.

20 43. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting a plurality of sub-divisions to said return conductor through progressively diminishing resistances, and a relay responsive to current delivered to the motor of a car on a sub-division ahead controlling said contactors.

25 44. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting a plurality

30 of sub-divisions to said return conductor through progressively diminishing resistances, and a relay responsive to current delivered to the field of a motor on a car on a sub-division ahead controlling said contactors.

35 45. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting a sub-division to said return conductor through a resistance and means for subjecting one or more of the following sub-divisions to progressively increasing voltages, and a relay responsive to current delivered to the motor of a car on a sub-division ahead controlling said contactors.

40 46. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting a sub-division to said return conductor through a resistance and means for subjecting one or more of the following sub-divisions to progressively increasing voltages, and a relay responsive to current delivered to the field of a motor on a car on a sub-division ahead controlling said contactors.

45 47. In an electric railway system, a contact conductor extending along the trackway and separated into sub-divisions, a source of current, a contactor for each sub-division controlling supply of current from said source of current, said contactors in one position connecting a plurality of sub-divisions directly to said source of current, a return contact conductor, said contactors in another position connecting a plurality of sub-divisions to said return conductor through resistances diminishing progressively in the direction of travel and means for subjecting one or more of the following sub-divisions to progressively increasing voltages, and a relay responsive to current delivered to the motor of a car on a sub-division ahead controlling said contactors.

50 48. In an electric railway system, a contact conductor extending along the trackway and separated into sub-divisions, a source of current, a contactor for each sub-division controlling supply of current from said source of current, said contactors in one

position connecting a plurality of sub-divisions directly to said source of current, a return contact conductor, said contactors in another position connecting a plurality of sub-divisions to said return conductor through resistances diminishing progressively in the direction of travel and means for subjecting one or more of the following sub-divisions to progressively increasing voltages, and a relay responsive to current delivered to the field of a motor on a car on a sub-division ahead controlling said contactors.

49. In an electric railway system, a car, a motor thereon, a sub-divided contact conductor extending along the trackway for supplying current to said motor, a return contact conductor, a source of current, a contactor in one position connecting a sub-division of said contact conductor to said return conductor, a second contactor, said first contactor in another position connecting said sub-division with said second contactor, said second contactor in one position connecting said sub-division directly to said source of current and in another position controlling means for subjecting said sub-division to reduced voltage, and a relay responsive to current delivered to the motor of a car on a sub-division ahead controlling said contactor.

50. In an electric railway system, a car, a motor thereon, a sub-divided contact conductor extending along the trackway for supplying current to said motor, a return contact conductor, a source of current, a contactor in one position connecting a sub-division of said contact conductor to said return conductor, a second contactor, said first contactor in another position connecting said sub-division with said second contactor, said second contactor in one position connecting said sub-division directly to said source of current and in another position controlling means for subjecting said sub-division to reduced voltage, and a relay responsive to current delivered to the field of a motor on a car on a sub-division ahead controlling said contactor.

51. In an electric railway system, the combination with cars, of motors thereon for driving the same, a contact conductor extending along the path of travel of said cars, said contact conductor divided into block sections, means for dividing each block section into a plurality of sub-sections, means for delivering to said sub-sections of contact conductor of a block section current progressively increasing in voltage in the direction of travel of said cars, an electro-magnetic switching means controlled by current delivered to a motor on a car on another block section for controlling said last named means, whereby a car traversing said

sub-sections of contact conductor has its speed progressively increased.

52. In an electric railway system, the combination with cars, of motors thereon for driving the same, a contact conductor extending along the path of travel of said cars, means for dividing said contact conductor into block sections, a source of current, and automatic means controlled by a car traversing another block section for causing the car to traverse the block at full speed or for braking the car or for restarting the car, said means when restarting the car applying to the motor thereof voltage correlated to the speed of the car.

53. In an electric railway system, the combination with cars, of motors thereon for driving the same, armature and field contact conductors extending along the path of travel of said cars, means for dividing an armature contact conductor into block sections, and electro-magnetic means controlled by current delivered from a field contact conductor to a motor of a car on one of said blocks for controlling a car on another of said blocks to brake or restart the same or to cause it to pass over the block at full speed.

54. In an electric railway system, the combination with cars, of motors thereon for driving the same, armature and field contact conductors extending along the path of travel of said cars, means for dividing an armature contact conductor into block sections, a relay controlled by current delivered from a field contact conductor to a motor of a car on one block section, and electro-magnetic switching means controlled by said relay and controlling a car on another block section to brake or restart the same or to cause the same to pass over said block at full speed.

55. In an electric railway system, a car, a motor thereon, a contact conductor extending along the path of travel of said car and divided into block sections, means associated with each block section for retarding said car by steps and for restarting said car, and means controlled by said car for automatically putting the block section in the rear in condition for bringing a car to rest.

56. In an electric railway system, a car, a motor thereon, a contact conductor extending along the path of travel of said car and divided into block sections, means associated with each block section for bringing said car to rest and for accelerating said car step-by-step, and means controlled by said car for automatically putting a block section in the rear in condition for bringing a car to rest.

57. In an electric railway system, a car, a motor thereon, a contact conductor ex-

- 5 tending along the path of travel of said car and divided into block sections, means associated with each block section for retarding said car step-by-step and accelerating said car step-by-step, and means controlled by said car for automatically putting the block section in the rear in condition for bringing a car to rest. 65
- 10 58. In an electric railway system, a car, a motor thereon, a contact conductor extending along the path of travel of said car and divided into block sections, and automatic means controlled by a car on another block section associated with each 70 block section for retarding said car by steps and for re-starting said car. 75
- 15 59. In an electric railway system, a car, a motor thereon, a contact conductor extending along the path of travel of said car and divided into block sections, and automatic means associated with each block section for bringing said car to rest and for accelerating said car step-by-step. 80
- 20 60. In an electric railway system, a car, a motor thereon, a contact conductor extending along the path of travel of said car and divided into block sections, and automatic means associated with each block section for retarding said car step-by-step and 85 accelerating said car step-by-step. 90
- 25 61. In an electric railway system, a car, a motor thereon, a contact conductor extending along the path of travel of said car and divided into block sections, a source of current, and automatic means associated with each block section for bringing said car to rest and for impressing on said motor voltage less than the voltage of said source of current for restarting said car. 95
- 30 62. In an electric railway system, a car, a motor thereon, a contact conductor extending along the path of travel of said car and divided into block sections, means associated with each block section for retarding 100 said car step-by-step and for re-starting said car step-by-step, and means controlled by said car for automatically putting the block section in the rear in condition for retarding a car, and for putting the second block section in the rear in condition for re-starting a car. 105
- 35 63. In an electric railway system, a car, a motor thereon, a contact conductor extending along the path of travel of said car and divided into block sections, means associated with each block section for bringing said car to rest and for accelerating said car step-by-step, and means controlled by said car for automatically putting a block 110 section in the rear in condition for bringing a car to rest, and for putting the second block section in the rear in condition for accelerating a car. 115
- 40 64. In an electric railway system, a car, a motor thereon, a contact conductor extending along the path of travel of said car and divided into block sections, a source of current, automatic means associated with a block section for retarding said car, for impressing upon said motor voltage less than the voltage of said source of current for re-starting said car, and for supplying full voltage of said source to said motor, and means responsive to the condition of another block section controlling said means. 120
- 45 65. In an electric railway system, a car, a motor thereon, a contact conductor extending along the path of travel of said car and divided into block sections, a source of current, automatic means associated with a block section for retarding said car, for impressing on said motor voltage less than the voltage of said source of current for re-starting said car, and for supplying full voltage of said source to said motor, and means responsive to current supplied to a block section in advance controlling said means to retard said car. 125
- 50 66. In an electric railway system, a car, a motor thereon, a contact conductor extending along the path of travel of said car and divided into block sections, a source of current, automatic means associated with a block section for retarding said car, for impressing on said motor voltage less than the voltage of said source of current for re-starting said car, and for supplying full voltage of said source to said motor, and means responsive to delivery of current to a second block section in advance controlling said means for re-starting said car. 130
- 55 67. In an electric railway system, a car, a motor thereon, a subdivided contact conductor extending along the trackway for supplying current to said motor, a return contact conductor, a source of current, a contactor, said contactor in one position connecting a subdivision of said contact conductor directly with said source of current, and in another position connecting a subdivision of contact conductor with said source of current through a resistance. 135
- 60 68. In an electric railway system, a car, a motor thereon, a subdivided contact conductor extending along the trackway for supplying current to said motor, a return contact conductor, a source of current, a contactor, said contactor in one position connecting a subdivision of said conductor directly with said source of current, and in another position connecting a subdivision of contact conductor with said source of current through a resistance, and means automatically controlling said contactor in response to position of another car. 140
- 65 69. In an electric railway system, a car, a motor thereon, a subdivided contact conductor extending along the path of travel

- of said car for supplying current to said motor, a return contact conductor, a source of current, a contactor, a second contactor; said contactors in one position connecting a subdivision of said contact conductor directly with said source of current, said first named contactor in another position connecting said subdivision of contact conductor to said source of current through a resistance and through said second contactor, and means responsive to presence of a car on another subdivision of contact conductor preventing said first named conductor taking its first named position.
70. In an electric railway system, a car, a motor thereon, a subdivided contact conductor extending along the path of travel of said car for supplying current to said motor, a return contact conductor, a source of current, a contactor, a second contactor, said contactors in one position connecting a subdivision of said contact conductor directly with said source of current, said first named contactor in another position connecting said subdivision of contact conductor to said source of current through a resistance and through said second contactor, and means automatically controlling said contactors in response to position of another car.
75. In an electric railway system, a car, a motor thereon, a subdivided contact conductor extending along the path of travel of said car for supplying current to said motor, a source of current, means for delivering current at voltage less than the full voltage of said source of current, a contactor, said contactor in one position subjecting a subdivision of said contact conductor to the full voltage of said source of current and in a second position to said lesser voltage, and means responsive to the presence of a car on another subdivision of contact conductor preventing said contactor taking its first named position.
80. In an electric railway system, a car, a motor thereon, a subdivided contact conductor extending along the path of travel of said car for supplying current to said motor, a return contact conductor, a source of current, a contactor, a second contactor, said contactors in one position connecting a sub-division of said contact conductor directly to said source of current and in another position connecting said second sub-division of contact conductor to said source of current through a resistance less than said first named resistance.
85. In an electric railway system, a car, a motor thereon, a subdivided contact conductor extending along the path of travel of said car for supplying current to said motor, a return contact conductor, a source of current, a contactor, a second contactor, said contactors in one position connecting a sub-division of said contact conductor directly with said source of current, said first named contactor in another position connecting said sub-division of contact conductor to said source of current through a resistance and through said second contactor, and said second contactor in another position isolating said sub-division of contact conductor from said source of current and connecting it to said return contact conductor, a third contactor controlling another sub-division of said contact conductor, said third contactor in one position connecting said second sub-division of contact conductor directly to said source of current and in another position connecting said second sub-division of contact conductor to said source of current through a resistance less than said first named resistance.
90. In an electric railway system, the combination with a car, of a motor thereon for driving the same, a sectioned contact conductor extending along the path of travel of said car, a return contact conductor, a movable contact member for connecting a section of said contact conductor to said return conductor for braking said car, and means for actuating said contact member controlled by another car, said contact member remaining unbiased in the position to which last actuated.
95. In an electric railway system, the combination with a car, of a motor thereon for driving the same, a sectioned contact conductor extending along the path of travel of said car, a return contact conductor, a source of current, a movable contact member in one position connecting a section of
100. In an electric railway system, the combination with a car, of a motor thereon for driving the same, a sectioned contact conductor extending along the path of travel of said car, a return contact conductor, a movable contact member for connecting a section of said contact conductor to said return conductor for braking said car, and means for actuating said contact member controlled by another car, said contact member remaining unbiased in the position to which last actuated.
105. In an electric railway system, the combination with a car, of a motor thereon for driving the same, a sectioned contact conductor extending along the path of travel of said car, a return contact conductor, a movable contact member for connecting a section of said contact conductor to said return conductor for braking said car, and means for actuating said contact member controlled by another car, said contact member remaining unbiased in the position to which last actuated.
110. In an electric railway system, the combination with a car, of a motor thereon for driving the same, a sectioned contact conductor extending along the path of travel of said car, a return contact conductor, a movable contact member for connecting a section of said contact conductor to said return conductor for braking said car, and means for actuating said contact member controlled by another car, said contact member remaining unbiased in the position to which last actuated.
115. In an electric railway system, the combination with a car, of a motor thereon for driving the same, a sectioned contact conductor extending along the path of travel of said car, a return contact conductor, a movable contact member for connecting a section of said contact conductor to said return conductor for braking said car, and means for actuating said contact member controlled by another car, said contact member remaining unbiased in the position to which last actuated.
120. In an electric railway system, the combination with a car, of a motor thereon for driving the same, a sectioned contact conductor extending along the path of travel of said car, a return contact conductor, a movable contact member for connecting a section of said contact conductor to said return conductor for braking said car, and means for actuating said contact member controlled by another car, said contact member remaining unbiased in the position to which last actuated.
125. In an electric railway system, the combination with a car, of a motor thereon for driving the same, a sectioned contact conductor extending along the path of travel of said car, a return contact conductor, a source of current, a movable contact member in one position connecting a section of

said contact conductor to said return contact conductor and in another position connecting said section of contact conductor with said source of current, and means for actuating said contact member controlled by another car, said contact member remaining unbiased in the position to which last actuated.

In testimony whereof I have hereunto affixed my signature in the presence of the 10 two subscribing witnesses.

KENNETH E. STUART.

Witnesses:

NOËL HANS HAMILTON,
K. SPARKES.

It is hereby certified that in Letters Patent No. 1,240,898, granted September 25, 1917, upon the application of Kenneth E. Stuart, of London, England, for an improvement in "Electric-Railway Systems," errors appear in the printed specification requiring correction as follows: Page 11, line 23, for the word "ssection" read *section*; page 15, line 43, claim 10, after the word "conductors" insert a comma; page 18, line 40, claim 33, for the compound word "sub-section" read *sub-sections*; page 20, line 60, claim 51, for the word "an" read *and*; and that the said Letters Patent should be read with these corrections therein that the same may conform to the record of the case in the Patent Office.

Signed and sealed this 20th day of November, A. D., 1917.

[SEAL.]

R. F. WHITEHEAD,
Acting Commissioner of Patents.

Cl. 246—36.
